(57) **CLAIM**

The ornamental design for an exhaust shield as shown and described.

DESCRIPTION

FIG. 1 is a perspective view of an exhaust shield, showing an embodiment of our new design.

FIGS. 2 is an enlarged detail view of a portion of the exhaust shield taken from FIG. 1.

FIG. 3 is a front elevational view of the exhaust shield.

FIG. 4 is an enlarged detail view of a portion of the exhaust shield taken from FIG. 3.

FIG. 5 is a rear elevational view of the exhaust shield.

FIG. 6 is a left side elevational view thereof.

FIG. 7 is a right side elevational view thereof.

FIG. 8 is a top plan view thereof.

FIG. 9 is a bottom plan view thereof.

FIG. 10 is a perspective view of an exhaust shield, showing another embodiment of our new design, which is a mirror image of the exhaust shield shown in FIGS. 1-9.

FIG. 11 is an enlarged detail view of a portion of the exhaust shield taken from FIG. 10.

FIG. 12 is a front elevational view of the exhaust shield.

FIG. 13 is an enlarged detail view of a portion of the exhaust shield taken from FIG. 12.

FIG. 14 is a rear elevational view of the exhaust shield.

FIG. 15 is a left side elevational view thereof.

FIG. 16 is a right side elevational view thereof.

FIG. 17 is a top plan view thereof; and,

FIG. 18 is a bottom plan view thereof.

Stippling in the drawings represents the three-dimensional contours of the design, and is not intended to indicate surface decoration. The broken lines shown in the drawings depict portions of the exhaust shield that form no part of the claimed design.
